HAIR TRIMMER

Norman V. Christensen, 325 1/4 S. New Hampshire Ave.,
Los Angeles, Calif.

Filed Aug. 28, 1961, Ser. No. 66,512

Term of patent 14 years

(Cl. D22—5)

Fig. 1.

Fig. 2.

Fig. 3.

Fig. 4.

Fig. 5.

FIG. 1 is a top plan view of a hair trimmer showing my new design.

FIG. 2 is a front elevational view thereof.

FIG. 3 is a side elevational view thereof as seen from the right of FIG. 2.

FIG. 4 is a rear elevational view.

FIG. 5 is a half scale front elevational view as it appears with the sliding blade container extended.

I claim:

The ornamental design for a hair trimmer, as shown.
